(57) CLAIM

The ornamental design for a spatula head for a device having a non-shaving head, as shown and described.

DESCRIPTION

FIG. 1 is a perspective view of the spatula head for a device having a non-shaving head (portions not claimed shown with broken lines).

FIG. 2 is a elevation view from a side thereof (portions not claimed shown with broken lines).

FIG. 3 is a elevation view of the rear thereof (portions not claimed shown with broken lines).

FIG. 4 is a elevation view of the front therof (portions not claimed shown with broken lines).

FIG. 5 is a plan view of the top thereof (portions not claimed shown with broken lines); and,

FIG. 6 is a plan view of the bottom thereof (portions not claimed shown with broken lines).

The broken line showing the spatula head coupled with the device in FIGS. 1-6 is for illustrative purposes only and forms no part of the claimed design.
